(57) **CLAIM**

The ornamental design for a peelable menstrual pad, as shown and described.

DESCRIPTION

FIG. 1 is a perspective view of my new peelable menstrual pad;

FIG. 2 is a top plan view of my new peelable menstrual pad;

FIG. 3 is bottom plan view of my new peelable menstrual pad;

FIG. 4 is a left end elevational view of my new peelable menstrual pad;

FIG. 5 is a right end elevational view of my new peelable menstrual pad;

FIG. 6 is a front elevational view of my new peelable menstrual pad;

FIG. 7 is a rear elevational view of my new peelable menstrual pad; and,

FIG. 8 is a partially exploded perspective view of my new peelable menstrual pad.

The broken lines shown in the figures are for illustrative purposes only and form no part of the claimed design.

The stippling shown in the figures represents surface textures.
